UNITED STATES PATENT OFFICE.

JOHN NEWTON STOKES, OF BENTONVILLE, ARKANSAS.

EXTENSION CAR-STEP.

1,159,288.

Specification of Letters Patent.

Patented Nov. 2, 1915.

Application filed May 14, 1914. Serial No. 838,560.

To all whom it may concern:

Be it known that I, JOHN N. STOKES, a citizen of the United States, residing at Bentonville, in the county of Benton and 5 State of Arkansas, have invented certain new and useful Improvements in Extension Car-Steps, of which the following is a specification.

This invention relates to improvements in 10 railway passenger or other cars, more particularly auxiliary steps or extension-steps therefor.

The invention has for its object to facilitate ingress and egress to and from, especially 15 passenger cars.

A further object is to provide for readily adjusting the step-extension for use and disposing it out of use.

A still further object is to carry out these 20 ends in a simple, economical and expeditious manner.

The invention therefore consists of an auxiliary or supplemental step or step-extension adapted to have slidable, or extensible 25 connection with the regular car-steps, also means for the application or adjustment of said auxiliary step or step-extension to the latter, substantially as hereinafter disclosed and defined by the appended claim.

30 In the accompanying drawings is illustrated the preferred embodiment of my invention wherein it will be understood that various changes and modifications may be made as to the detailed construction and arrangement of parts without departing from the spirit of the invention, and in which drawings:—

Figure 1 is an elevation of a passenger-car with my invention applied thereto, or 40 rather to the steps thereof, in extended and unextended positions, respectively. Figs. 2 and 3 are front views of the invention as assembled with the car-steps, detached from the car, the invention being in unextended and extended positions, respectively. Fig. 4 is a detached perspective view of the invention. Fig. 5 is a horizontal section taken on the line 4—4 of Fig. 4.

In carrying out my invention, I suitably 50 contrive a supplemental or auxiliary step, or step-extension, designated generally as 1, in approximately U-shaped outline, as clearly indicated in Fig. 4, the step proper 2 and the side or lateral forming portions thereof 3

being at right angles to each other. The 55 side or lateral portions 3, in providing for a sliding or extended action, are of suitable length for the purpose and adapted to be applied to the sides of the car-steps A, said side portions 3 having inwardly extending 60 flanges or guides 5 along their longitudinal edges, to overlie or engage the corresponding portions of the car-steps A. Said side portions 3 are provided, centrally about, with longitudinal slots 6 which receive studs 65 or projections 7 upon the sides of the car-steps, well down near or at the lower ends, and upon which studs or projections the auxiliary or supplemental steps or step-extension is adapted, as already indicated, to 70 have longitudinal or sliding movement, in order to provide for the lowering thereof, for facility of the passengers of the car in entering and leaving the latter.

A suitable lever or handle-equipped crank 75 shaft 8 is journaled or supported in, and extends through the sides of the car-steps, near or at the upper end thereof, the handle or lever of said shaft being designated as 9. One arm of end 10 of the shaft 8 and the lever or handle 9 thereof are connected to the side or lateral portions 3 of the auxiliary or supplemental step or step-extension by rods or links 11, in twin, pivoted to said parts, the connection between said rods and 80 said side-portions 3 being adjacent the upper ends of the latter, whereby it will be observed that by suitably actuating said lever, said step-extension may be lowered within 85 easy or convenient stepping distance between the car and the street for the passengers, in leaving and entering the car, as before indicated. It will be further observed that, after using the auxiliary step or step-extension and in again elevating it to initial 90 or former position, by suitably disposing the lever in "dead-center" alignment with the rods 11, the desired locking action is obtained for the suitable retention of the auxiliary step or step-extension in elevated position until further needed. 100

I claim:—

A device of the type described, including an approximately U-shaped step-forming member fitted to slide upon the lower end of 105 an extension-step of a passenger-carrying vehicle, a bail or U-shaped lever with its bail forming portion fulcrumed in said exten-

sion-step and links having their lower ends connected to said slideable step-forming member, the opposite ends of said links being connected to one arm of the bail forming a portion of said lever and to the lever proper, respectively.

In testimony whereof I affix my signature in presence of two witnesses.

JOHN NEWTON STOKES.
